UNITED STATES PATENT OFFICE

129,108

DESIGN FOR A CAMERA CARRYING CASE

Joseph A. Sprague, Rochester, N. Y., assignor to
The Folmer Graflex Corporation, Rochester,
N. Y., a corporation of Delaware

Application February 12, 1941, Serial No. 98,961

Term of patent 7 years

To all whom it may concern:

Be it known that I, Joseph A. Sprague, a citizen of the United States, residing at Rochester, county of Monroe, and State of New York, have invented a new, original, and ornamental Design for a Camera Carrying Case, of which the following is a specification, reference being had to the accompanying drawings, forming part thereof, wherein:

Fig. 1 is a front elevational view of a camera carrying case, embodying my new design;

Fig. 2 is a right hand, end elevation of the same; and

Fig. 3 is a top plan view of the case in open position.

I claim:

The ornamental design for a camera carrying case, substantially as shown.

JOSEPH A. SPRAGUE.
